(57) **CLAIM**

The ornamental design for a cordless telephone handset cradle, as shown and described.

DESCRIPTION

FIG. 1 is a front perspective view of the cordless telephone handset cradle of the present invention, wherein a cordless telephone handset shown in dotted lines is cradled; and, FIG. 2 is a top plan view of the cordless telephone handset cradle.

The broken line showing of a handset in FIG. 1 is for illustrative purposes only and forms no part of the claimed design.
